UNITED STATES PATENT OFFICE.

DENNIS JORDAN AND JAMES W. DUNCAN, OF SAN FRANCISCO,
CALIFORNIA.

CONSTRUCTION OF LEVEES, &c.

SPECIFICATION forming part of Letters Patent No. 600,832, dated March 15, 1898.

Application filed June 23, 1897. Serial No. 641,983. (No model.)

To all whom it may concern:

Be it known that we, DENNIS JORDAN and JAMES W. DUNCAN, citizens of the United States, residing in the city and county of San Francisco, State of California, have invented 5 certain new and useful Improvements in the Construction of Levees and other Artificial Embankments, of which the following is a specification.

10 Our invention relates to an improvement made in the construction of levees and similar artificial embankments for protecting lands from inundation; and the improvement consists, essentially, in a structure formed or 15 produced mainly of concrete piers or pillars and concrete slabs arranged in parallel rows and longitudinally in the levee and a filling of rock or other material between said rows, such structure being located partly below and 20 partly above the bottom or base upon which the levee is erected.

This improvement is well adapted for obtaining a firm foundation upon or for strengthening those portions of a levee that are required 25 to be carried across a quicksand or other soft bottom in the line of a levee, where a solid or firm base or foundation cannot be secured by the ordinary methods of construction at present followed without going to great expense in filling in and rendering such soft or 30 weak spots sufficiently solid to bear the levee or to resist the erosive or undermining action of the water, and it is also adapted for strengthening those portions of a levee already 35 constructed where there is more or less danger of an undermining or weakening action of the water upon the lower portion of the levee.

The nature of our said improvements and 40 the manner in which we proceed to construct, apply, and carry out the same will be fully understood from the following description and the accompanying drawings, forming part of this specification, and to which reference is 45 herein made by letters.

In the said drawings, Figure 1 is a top view 50 of a section of our structure as applied for strengthening a portion of a levee that is carried across quicksand or similar soft bottom 55 in the line of a water-course and before the levee is completed. Fig. 2 is a vertical sec-

tion taken transversely through the finished structure. Fig. 3 is a plan or top view of one of the slabs of the structure, with a portion of the surface broken away to show the internal 55 construction. Fig. 4 is an end view of Fig. 3.

A indicates a levee or embankment, B the foundation or bottom on which the same is built, and C the river or body of water on the outer side of the levee.

D are piers or pillars of concrete sunk partly into the bottom B and standing partly above the bottom at intervals of distance apart and in two rows or lines substantially parallel with each other, following the lines 60 or general direction of the embankment.

E are concrete slabs standing substantially perpendicular or in an upright position against the piers from the inside of the space between the two rows. Each slab in length 70 horizontally across the face is equal to the distance between one pier and the next in the row, measuring from center to center, and the height of the slab is about equal to its length. The space inclosed between the two rows or 75 lines of slabs is filled with rocks or broken stone or any available material producing a solid wall F.

The piers D are built by first sinking a caisson d^x of sheet-iron into the bottom B and 80 then filling in the concrete, the caissons being of such cheap construction that they may be left in position after the pier is formed. Each pier is carried up to a greater or less height above the bottom B, and usually up to the 85 ordinary level of the body of water above the bottom.

The slabs E are formed of concrete, with two sets of strengthening-rods E' E² embedded and interwoven in the concrete in such 90 manner as to secure the greatest strength in the direction of the lines of force which the slab is called upon to sustain while being handled and when in position. These rods consist of a set or series E', running horizontally from end to end, and a second set or series E², running perpendicularly from top to bottom and woven or interlaced with the horizontal rods in an alternate manner similar to basket-weaving, as shown in Figs. 3 and 4. The object of this construction is to obtain a relatively thin and light slab possessing the re-

quired strength to resist the pressure brought against it when in position supported at the ends, and also capable of being handled and laid in place without danger of fracturing, and 5 these points we secure by the application and combination of the two sets of interwoven rods E' E².

The slabs are laid in position against the piers from the inside of the inclosed space in 10 two parallel lines or rows, after which the inclosed space between the rows is filled with the material F—such as broken stone, gravel, or any such available material—and the same closely packed against the slabs. The earth- 15 work forming the embankment is then built up from the bottom or bed to the required height over and entirely covering the concrete work, and the same is finished with the sloping walls or faces in the usual manner of 20 constructing levees and such like embankments.

As thus constructed and applied it will be seen that the improvement embraces a means of strengthening a levee by interposing be- 25 tween the two faces of the embankment a wall or perpendicular structure mainly of concrete piers and slabs standing partly above the base or bottom on which the embankment is built and extending partly into such base.

30 The width of the concrete structure will necessarily vary with and be governed to some extent by the special conditions of the case, such as the height and thickness of the embankment and the pressure which it is re- 35 required to sustain under ordinary and extraordinary occasions. The structure can be made of much less thickness in proportion to its height, however, than an ordinary construction of wall without the piers and slabs.

This improvement affords a rapid and ef- 40 fective means of strengthening and protect- ing at one or more points a levee or embank- ment already constructed, and at a compara- tively small expense.

Having thus fully described our invention, 45 what we claim as new, and desire to secure by Letters Patent, is—

1. In the construction of levees and other like embankments, a strengthening structure 50 consisting of concrete piers or pillars in par- allel rows at intervals apart extending partly below and standing partly above the bottom or natural base of the embankment, concrete slabs resting against and supported by said pillars and a filling of solid material between 55 said rows of slabs.

2. In a levee or other like embankment the combination of the concrete piers or pillars, in parallel rows at intervals apart, the con- 60 crete slabs resting against said pillars and closing in the space between the rows there- of, and the filling material between the rows of slabs, constructed and applied for opera- tion as hereinbefore described.

3. In a concrete structure for strengthen- 65 ing levees and other like embankments, the combination of the concrete piers or pillars in spaced rows, and concrete slabs having the horizontal rods E and the vertical rods E' inter- 70 woven with the horizontal rods and em- bedded in the concrete.

In testimony that we claim the foregoing we have hereunto set our hands and seals.

DENNIS JORDAN. [L. S.]
JAMES W. DUNCAN. [L. S.]
